[57] CLAIM

The ornamental design for an electronic notepad, as shown and described.

DESCRIPTION

FIG. 1 is a top front right side perspective view of an electronic note pad showing our new design wherein a pen is shown in a receptacle at the upper end of the pad in broken lines for illustrative purposes only and forms no part of the claimed design.

FIG. 2 is a bottom side elevational view thereof;

FIG. 3 is a top side elevational view thereof;

FIG. 4 is a front elevational view thereof;

FIG. 5 is a right side elevational view thereof;

FIG. 6 is a rear elevational view thereof; and,

FIG. 7 is a left side elevational view thereof.
